John B. Francis, Louisa County, Virginia,

Letters Patent.

The hedge-cutter referred to in these Letters Patent and working part of the same, containing a description in the words of the said John B. Francis, himself of his improvement in the machine for cutting or cutting out the ends of hedges or wheel conveyances to receive the boxes.

To all to whom these presents shall come.—
Be it known that I, John B. Francis, in the County of Louisa and State of Virginia, have invented a new and useful improvement in cutting or cutting out the ends of wagons and all other wheel conveyances to receive the boxes, also the cups for the bunch-pins, and the following is a full and exact description of the construction & operation of the said machine as invented or improved by me according to the model here with presented. First, an iron spindle about two feet six or eight inches long, made round and smooth of uniform size, and large enough to prevent it from breaking, with one end pointed and a mortise about two inches long a foot at least from the pointed end to receive the shanks of the bits and bunge, with a tapering screw or wedge inserted in place of the shanks of the said bits to tighten, slacken them, &c as to suit the different sizes of boxes will be necessary, with shanks to fit the mortise in the spindle, leaving room between it and them, now or usage to receive the shank of the bunge. The blade of the bit should extend backward to the edge of the edge with the inner corner from end to prevent splitting or roughing in cutting. The bunge should be made to project from the edge of the bit so as to be cut in the blade so as to give the bit a proper edge or point, & from taking too much wood. In the next place make the mortise flat for the end of your wagon, and try about four or five efforts to each other.

These

More of one plate to suit the large end and one of the other
 the smaller end of the hubs, also two long wings to each plate
 opposite each other about one and a half inches longer from the
 end of the plate than the sum of diameter of the largest hubs, with a
 point of iron three inches in length either twisted or rounded
 each wing at equal distances from the center, also half inch
 holes made near the extremities of the long wings with
 set-screws of brass, two iron rods must be made to fit the
 said holes with long screws out on one end of them the
 other end with a head and hole through it to receive and
 to turn them, the rods should be about twenty one inches long,
 the plates must have holes in their centers to admit the pinion
 the tighter the better, so that it can be inserted or drawn out with
 ease. There is another gauge necessary which is a bar of iron
 made to fit the spindle with substance sufficient to admit a
 wedge or key to tighten and hold it stationary, it will also be
 necessary for all persons using said machine to provide
 wooden wheels (which I shall denominate center wheels)
 made to fit the spindle, and the size of different sized
 boxes. The manner of using said machine is as follows:
 The hub must be gouged out in the usual way to the inside
 of the boxes, then the center wheels introduced into each and
 the spindle passed through them, the points to be slipped
 on the spindle at their respective ends, the long screws to be
 inserted into their places in the wings with the wedge lying between
 the spokes of the wheel; the points are then driven into the
 ends of the hub and the screws are turned up to hold them
 to their places; the spindle is then drawn out and the center
 wheels taken out, the spindle is then returned and the bit
 made first mentioned being placed in the machine and made
 tight with the tapered screw or wedge, the spindle is then
 driven through the hub with the help of the bit, the said gauge
 is then taken off, and the gauge and the pinion and hub

64634

for which it is to be bored will fit in depth in between the plate and gauge. The gauge is then made fast with its wedge. The wheel is to rest on the spindle, which is placed with the end on the upright or frame made for the purpose with the square and about eight or nine inches lower than the other, the upper bar is slipped on the square and made secured fast to the frame or upright which holds the spindle from turning. The wheel is then turned briskly round with the plates and long screw keys, with the weight in this inclined position bearing against the bit and gauge until the plate comes down to the circular gauge. The operation is then completed.

If the spindle is then drawn out the wheel is turned round presenting the other end of the bit the spindle retained a suitable bit introduced and the operation performed as before the cap for the lynch-pin is bored out in like manner. The whole operation is performed with the greatest facility and accuracy, it is believed that the whole operation of boring the hubs and then wedging in a set of boxes will not occupy more than two hours by one person, whereas by the usual process, it is considered by wheelwrights to be a full days work and is posset of accuracy and solidity, this machine will be far preferable, as it cuts smooth in the most snug or closely joined work.
